ELECTRIC CONNECTOR

Robin Gray, Stockport, England, assignor to The
Electric Storage Battery Co., a corporation of
New Jersey

Application January 13, 1943, Serial No. 472,201
In Great Britain February 16, 1942

5 Claims. (Cl. 173—259)

This invention relates to electric connectors, and particularly to heavy duty electric connectors such as may be used for example on storage battery installations, and has for its object to provide a compact, lightweight, highly efficient construction, which can be readily connected and disconnected, and which is substantially foolproof.

A further object is to provide a connection which will produce highly concentrated contact pressure between the parts to be electrically connected without imposing undue strain on the threads of the pressure applying nut and terminal post.

A further object is to provide a connection in which the pressure applying nut cannot be loosened by relative motion between the parts to be connected, so that no locking provision is required for the nut.

Further objects and advantages of this invention will become apparent as the following description proceeds and the features of novelty which characterize this invention will be set forth in the claims appended to and forming a part of this specification.

A terminal for connecting two conductors in accordance with this invention comprises a tongue like member upon one conductor end adapted to pass into and through a slotted terminal post provided on the other conductor end. The tongue has a notch in its underside which cooperates with a projection at the base of the slot in the terminal post. The projection is of slightly greater contained angle than the angle of the notch of the tongue, and a terminal nut, which screws on to the terminal post, is adapted to bear directly upon the back or upper surface of the tongue at opposite sides of the notch so as to exert balanced and intense pressure upon the two narrow contact areas of the projection and notch.

The invention further comprises the provision of a screw which passes co-axially through the terminal nut and threads into the tapped upper portion of the slotted post so as to brace the post internally and prevent complete withdrawal of the terminal nut, the latter having an outer portion of hard rubber or other insulating material.

For a more complete understanding of this invention reference should be had to the following detailed description taken in conjunction with the accompanying drawing in which:

Figure 1 is an elevation, partly in section, of

the improved connector assembly of this invention; and

Figure 2 is an elevation of the post portion of this invention viewed at right angles to the plane of Figure 1.

In the drawing 16 represents the end of an electric conductor on which is mounted or secured a terminal post 11. This post comprises a base portion 12, which may be cylindrical or rectangular in plan, surmounted by an externally threaded cylindrical portion 13. The upper part of the terminal post is bifurcated by a slot 14 (see Figure 2) which extends downward through the cylindrical portion 13 and part way into the base portion 12. At the bottom of the slot 14 is a projection 15 which in the specific embodiment illustrated is of inverted V shape.

Provided to cooperate with the post terminal 11 is a cable terminal which consists of a cylindrical portion 18 provided with a bore 17 adapted to receive the end of an electric conductor (not shown). At its opposite end this cable terminal is provided with a flattened portion or tongue 19 adapted for insertion in the slot 14. This flattened portion has a notch 18, in this instance inverted V shaped, on the under side adapted to receive the inverted V shaped projection 15 at the bottom of the slot 14. The contained angle of the projection 15 is somewhat greater than that of the notch 18, so that the cable terminal makes contact with the post terminal along the two lines of restricted area 20.

To secure the cable terminal in position there is provided a nut 21 having an outer portion 22 of insulating material, such as hard rubber, in which is molded a cylindrical metallic insert 23 which is internally threaded so as to cooperate with the external threads provided on the cylindrical portion 13 of the post 11. The metallic insert has a lower flange portion 24 which projects below the insulating portion 22. When screwed down on the post 11, the flange 24 bears upon the top of the tongue 18 at opposite sides of the V notch. In this way an intense balanced pressure, backed by substantial masses of metal, can be exerted on the narrow contact areas thereby insuring high electric efficiency. It is to be further observed that the engaging surfaces of the flange 24 of the insert 23 and the tongue 18 of the terminal 16 provide a further pair of independently engaging highly stressed contact areas which are highly efficient electrically.

Due to the fact that the contained angle of the V projection 15 is greater than the contained angle of the inverted V shaped notch 18, the con-

tact areas of the terminal are self-cleaning when pressure is applied through the nut 21.

Provided in the walls of the slot 14, near the top thereof, is a threaded portion 28 which is adapted to receive a screw 26. The bore of the upper portion of the terminal nut 21 is enlarged or counterbored so as to receive the head of the screw 26 to permit it to be threaded into the post when the terminal nut is in position. With this construction the screw 26 serves to strengthen the bifurcated portion of the post from the inside, whereas the metallic insert 23 strengthens the post from the outside. The head portion of the screw 26 projects beyond the outer edge of the post so as to engage the ledge 27 formed by enlarged bore of the terminal nut. In this way detachment of the nut 21 from the post is prevented so long as the screw 26 is in position. The shoulder 27 is so positioned that the nut can be backed off sufficiently far to permit removal of the tongue 18.

From the foregoing description it will be observed that I have provided an improved terminal connector which is simple in construction and easily assembled. It is to be particularly observed that the improved connector of this invention is inherently self locking and obviates the use of locking or other washer members between the nut and terminal. The cable terminal 16 cannot be rocked from side to side in the slotted terminal post 11 and wedging action of the cooperating V's 18 and 19 automatically takes up all play when the nut is tightened.

While a single embodiment of this invention has been described in detail, it is obvious that modifications can be made therein. For example, if desired, the portion 18 of the terminal member 16 could be constructed so that there is a degree of flexibility at the apex of the V slot 19 therein. In this way the contact areas at the edges 20 would be increased as the pressure applied to the top surface of the tongue 18 through the nut 21 increases. Furthermore the cooperating notch and projection could be other than V shaped if desired. It is therefore contemplated by the appended claims to cover all such modifications as come within the true spirit and scope of this invention.

I claim:

1. An electrical connector comprising a slotted element adapted to be secured to one electrical conductor, a flattened element for engaging said slotted element and adapted to be connected to a second electrical conductor, a projection in said slotted element at the base of said slot, a notch in said flattened element adapted to engage said projection and having a cross sectional area of opening at its widest portion less than the cross sectional area of said projection below the top portion thereof so that when said notch engages said projection substantially a line contact is attained, a terminal nut threaded on said slotted portion and adapted to engage the upper surface of said flattened portion on opposite sides of said notch so as to bring said projection and notch into engagement and produce an area of concentrated contact pressure along the lines of contact between said notch and said projection.

2. A connector assembly comprising a post element adapted to be electrically connected to one electric conductor, a tongue element adapted to

be connected to a second electric conductor, a slot in said post element adapted to receive said tongue element, an inverted V shaped projection in the bottom of said slot, an inverted V shaped notch in the under side of said tongue element having a contained angle less than that of said projection whereby when said notch and said projection are in engagement line contact is obtained, and means threadedly engaging said post element and adapted to bear on the upper side of said tongue element on opposite sides of said notch bringing said projection and notch into engagement and producing balanced high contact pressures at said line contacts.

3. In an electric connector assembly, the combination of an externally threaded terminal post bifurcated by a longitudinal slot having at the bottom an inverted V shaped projection, a conductor terminal having a flattened tongue inserted in the slot and projecting on both sides of said slot, said flattened portion having an inverted V shaped notch of lesser contained angle than that of said V shaped projection and adapted to fit over said projection, and a clamping nut threaded over the terminal post and bearing against the upper face of the tongue on each side of the post whereby concentrated contact pressure is produced between the tongue and post along the lines of contact between the edges of the notch and the faces of the projection.

4. A terminal connector assembly comprising a first member having a slot therein, a second member having a thickness slightly less than said slot and adapted to be received therein so that portions project on opposite sides of said first member, a notch in said second member, a projection at the bottom of the said first member adapted to be engaged by the walls forming said notch in said second member, the surfaces of said projection and the walls of said notch lying at an angle, the contained angle of said walls being less than the contained angle of said surfaces so that as said notch and projection are brought into engagement the lower edge of said notch slides along the surface of said projection and when said projection and notch are in engagement substantially a line contact is formed between said lower edges of said notch and the surfaces of said projection, a nut adapted to be threaded on said first member and to engage said projecting portions of said second member to force said notched portion down onto the surfaces of said projection and establish contact areas under large but equalized pressures, and removable means for preventing said nut from being completely removed from said first member.

5. A terminal connector assembly comprising a slotted member having a V shaped projection in the base of the slot therein, a second member adapted to be received in and project through said slot, a V shaped notch in said second member having an included angle less than the angle of said projection, and a nut threadedly engaging said first member and having a flange adapted to engage portions of said second member on opposite sides of said notch to bring and firmly hold the lower edges of said notch in engagement with the surfaces of said projection.
